CLAIM

The ornamental design for a flange for compressor impeller, as shown and described.

DESCRIPTION

FIG. 1 is a front view of a flange for compressor impeller showing our new design.

FIG. 2 is a top view thereof.

FIG. 3 is a left side view thereof.

FIG. 4 is a right side view thereof.

FIG. 5 is a cross-sectional view taken along line 5-5 in FIG. 4; and,

FIG. 6 is a reference perspective view thereof.
